UNITED STATES PATENT OFFICE.

JAMES LYON GARFIELD, OF DREXEL HILL, PENNSYLVANIA.

VISIBLE LOOSE-LEAF DEVICE.

Application filed August 25, 1927. Serial No. 215,437.

This invention relates to loose-leaf devices such as loose-leaf binders, card indexes or the like in which the sheets or cards are clamped at one side in vertically overlapping relation with both sides of each sheet or card accessible for entries. This invention is particularly useful in loose-leaf account ledgers used in machine posting.

One object of the invention is the provision of a loose-leaf sheet which is adapted to be added to other like sheets and to automatically space itself in overlapped relation and to keep that relation without the support of the panel or other holding means, even if the sheets are put through a regular typewriter as a group. Another object of the invention is to provide a visible loose-leaf side-hold panel in which a sheet may be readily removed or inserted at any point in a group of sheets without disarranging the other sheets. Another object of the invention is to provide a flat loose-leaf visible ledger composed of panels each of which can be put in a flat typewriter and the sheets typed without removal from the panel. A further object of the invention is the mounting of these side-hold panels themselves in horizontal overlapped relation thus giving immediate visibility to all the sheets in the whole device. Other objects will become apparent to those skilled in the art after reading the following description.

In the following specification it should be understood that the word "sheet" includes paper, card or any other form of flexible sheet material, and where in the claims the word "book" is used it should be understood that any type of loose-leaf device including binders and card indexes are intended to be included.

40 In the drawings—

Fig. 1 is a view showing a book embodying the invention opened out, certain portions of the sheets and panels being broken away;

Fig. 2 is a perspective view of the central lower portion of the book shown in Fig. 1;

Fig. 3 is an elevation of one end of the book when closed;

Fig. 4 is an exploded view in perspective showing part of one panel;

Fig. 5 is a perspective of a portion of two sheets showing the manner of assembling one sheet above the other; while

Fig. 6 is an end elevation of a modified form of clamp.

55 In visible loose-leaf devices of the type to

which this invention relates, it is necessary that the sheets be individually capable of ready removal from and insertion in their place in the book. According to the invention each sheet 10 has a single tongue or lip 11 near the lower left-hand corner, which tongue is preferably formed as a single lobe facing toward the upper edge of the sheet i. e., with the line joining the base points parallel to the lower edge of the sheet. Each sheet is adapted to be inserted behind the lip of the sheet below for the purpose of obtaining the overlap and nesting the cards together. The lip being near the lower edge of the sheet, the degree of vertical overlap is only a small part of 70 height of the sheet.

For the purpose of aligning the sheets I prefer to form a corrugation or corrugations such as a shallow groove or depression 12 running from top to bottom of each sheet near its left 75 edge. By hot-pressing this into shape the sheet will hold it permanently. This serves to assist in justifying the sheets yet leaves them free for insertion or removal. It is also desirable to give the left edge portion 14 of the 80 sheet beyond the groove a downward tendency and the lip 11, which can be located in the groove 12, an upward tendency. The lower left-hand corner 15 of each sheet, namely, the one adjacent the lip 11 is rounded for the purpose of assisting in the assembling of the sheets, especially when a sheet is to be inserted in the middle of a group already aligned. The purpose of the downward inclination of this edge portion 14 is to assist the rounded corner 90 15 in leading under the lip 11 of the sheet below. The edge portion 14 having a permanent downward tendency the corner 15 of the sheet being inserted will be led down under the lip 11 with a certainty never heretofore attained. Thus, when a sheet is to be inserted in the middle of a group of sheets already aligned, the new sheet is slipped under the sheet above it until the lower edge of the sheet above rests in the lip 11 of the new sheet. 95 The new sheet is then slid to the left until its curved corner rides under the lip and against one base point of the lip below, after which the curved corner of the new sheet pushes that sheet and all above it up until the sheets 100 are properly spaced. The grooves then come into alignment with each other and the new sheet is in place. A group of sheets thus assembled can be manipulated as a separate unit, even grasped in the hand and run 110

through a regular typewriter for the purpose of typing headings etc., without the sheets getting out of alignment.

The sheets are mounted in a panel composed of a clamp and a back 16 hingedly attached to the clamp as by cloth strips 17 embracing the folded edge 18 of the lower clamping bar 19. This clamping bar 19 and the cooperating upper clamping bar 20 may be made of sheet metal and fastened together by a series of hinge lugs 21 and a pintle 22 as shown in Figs. 1 to 4. The clamp is of the tongue and groove variety, a tongue 23 on the upper clamping bar gripping the sheets 15 against the lower clamping bar. This tongue 23 is formed by rolling the free longitudinal edge of the upper bar 20 in the form of a rigid flat hollow tube, spaced from the hinge knuckles a distance about equal to the width 20 of the edge portion 14 of the sheets. If desired additional rigidity can be given to the upper clamping bar by putting inside the folded tube thus formed at the outer edge of the bar, a strip 24 of spring metal which is 25 bowed downwardly at the middle, thus preventing the upper clamping bar from gradually becoming bowed up as a result of the pressure of the sheets in the binder.

For the purpose of holding the clamp closed 30 a sliding clip 25 is provided at each end of the upper clamping bar 20. One arm of each clip is secured within one end of the tongue 23 of the upper bar by any suitable means. The free arm of the clip is spaced at such a distance 35 from the secured arm that when the clamp is closed and the clip is pushed into the tube formed by the tongue 23 the free arm engages the outer surface of the lower clamping bar 19 and holds the two bars tightly together 40 as shown in Fig. 2. When the clips are pulled out the clamping bars will be opened to a convenient angle by coiled springs 26, placed at intervals on the rod 10 between the hinge knuckles of the clamping bars.

The lower clamping bar is preferably formed with a depression therein to receive the tongue 23 of the upper clamping bar. This formation is obtained by the outer folded edge 18 above referred to and by an angled strip 27 riveted or otherwise fastened on top of the lower clamping bar adjacent the hinge knuckles. This strip is of such a width that the surface of the lower clamping bar proper between the strip 27 and the folded edge 18 50 forms a depression adapted to receive the tongue 23 of the upper clamping bar. The corrugation or groove 12 in the sheets are adapted to fit into this depression in the lower clamping bar and the tongue on the upper 55 clamping bar is adapted to grip the sheets on top when it is desired to bind the sheets in position. This angled strip 27 has an upturned edge 28 adjacent the hinge knuckles extending for the full length of the panel, this edge 60 serving as a registry edge assisting the de-

pression in the lower clamping bar to align the sheets properly when put into the panel. It will be noted that with the construction of panel and sheet described, the sheet will fall automatically into proper alignment and push to the left until the left edge of the sheet touches the registry edge 28 of the angled strip 27. The edge portion 14 of the sheets overlies the angled strip 27 when the sheet is in position, but that angled strip is so low 75 that this edge portion is not gripped—the gripping pressure of the entire clamp being concentrated at the tongue 23. The angled strip 27 can be omitted if desired without departing from my invention.

I prefer to attach to the clamping bar a back 16 on which the sheets may rest, this back being made of any suitable material such as cardboard. In the example illustrated in the drawings, the right edge of this back is 80 folded upon itself forming a guiding edge 30 for the right hand edges of the sheets. It will be obvious that a glance down the right side of this back will show whether or not the sheets are in proper alignment and that since 85 the back is hinged to the clamp it can be swung out of the way when handling of the sheets requires it. This edge has another important function in that when a sheet or group of sheets is being removed from the 90 panel this right edge assists in holding in alignment those sheets which are not being removed. By having the back hinged to the clamp, by the cloth strips 17 already mentioned, the backs of the sheets are accessible 95 and can be written or typed upon at will in a flat bed typewriter as well as the fronts without removing the sheets from the panel.

A modified form of clamp is shown in Fig. 6 in which the coiled springs 26 are done away with. In this structure the upper and lower clamping bars 35, 32 are joined by a spring back 31 whose normal position is the open one shown in the drawing. With this structure a slightly different lower clamping bar 32 110 can be used which is bent in such a manner as to eliminate the necessity for the angled strip 27, the spring back 31 being of such a size as to still prevent any clamping action on the edge portion 14 of the sheets. It 115 should be understood that the clamp may be located at the right side of the sheets if desired.

When a book of greater capacity than one panel is desired a cover 33 can be employed 120 with a series of panels hingedly mounted in this cover in a manner which will now be described. For the purpose of mounting each panel the cover is equipped with a pair of hooks 34 at the top and bottom edges of the binder facing toward each other and adapted to hook into the end hinge knuckles of the clamping bar, the pintle 22 of the clamping bar being short enough to permit the entering 125 of these hooks. One of each pair of 130

hooks 34 is rigidly mounted in the cover but the other hook is held by tension spring means to permit insertion in and removal of the panel from the cover. The hooks are spaced 5 apart left and right a distance a little more than the width of the clamping bar, this overlapping relation being clearly shown in Fig. 3. It will be observed that by assembling the panels in this manner the clamping bars lie 10 substantially flat with their thick portions partly in line with each other rather than on top of each other. Furthermore, this construction makes visible the right-hand lower corner of each sheet in every panel. The 15 cover of course is wide enough to afford protection for all the panels.

I claim:

1. A loose leaf sheet having a corrugation formed vertically across it at one side and a 20 lip near said side, the base line of said lip being substantially at right angles to said corrugation.

2. A loose leaf sheet having a hot-pressed groove extending across it near the left edge 25 in combination with a lip in said groove near the lower left-hand corner of the sheet facing the upper edge of said sheet.

3. A loose leaf sheet having a curved corner, and a groove extending from said corner 30 to the vertically adjacent corner in combination with a lip located wholly within said groove adapted to hold a similar sheet in overlapped relation longitudinally of the groove.

35 4. A loose leaf sheet having its lower left-hand corner curved, a permanent groove extending vertically across said sheet at the left side in combination with a lip located wholly within said groove and adjacent said 40 curved corner, having its base line parallel to the lower edge of said sheet, said lip having a slight permanent upward bend substantially as described.

5. In a loose leaf device, a panel comprising 45 a clamp in combination with a back hinged to said clamp, said clamp being adapted to align the left edges of the sheets and said back being adapted to align the right edges of the sheets.

50 6. In a loose leaf device, a panel comprising a clamp, a back hinged thereto adapted to hold the right edges of the sheets in alignment, said clamp having a tongue and groove adapted to grip overlapped sheets and having 55 a left edge adapted to hold the left edge of said sheets in register, substantially as described.

7. In a loose leaf book, a cover, a series 60 of panels hingedly mounted in overlapped relation therein, each panel comprising a clamp adapted to grip a series of vertically overlapped sheets, and a back hinged to said clamp and adapted to support said sheets and

keep the right edges thereof in alignment, substantially as described. 65

8. In a loose leaf device, a panel having a clamp comprising a rigid grooved lower clamping bar and a rigid upper clamping bar fitting said groove, clips adapted to hold said clamping bars in closed relation and a 70 back hinged to said clamp adapted to support the sheets in the clamp and to hold their right edges in register, substantially as described.

9. In a loose leaf device, a panel having 75 an upper clamping bar, having a folded outer longitudinal edge thereon, a flat spring strip carried within said folded edge and clips carried in the ends of said folded edge, in combination with a lower clamping bar, 80 grooved to receive the folded edge of said upper clamping bar, and adapted to be engaged by said clips.

10. In a loose leaf device, a panel having 85 an upper clamping bar, having a folded outer edge, means carried by said upper clamping bar to engage a lower clamping bar, and a lower clamping bar grooved to receive the folded edge of said upper clamping bar, in combination with a back hinged to said 90 lower clamping bar, a folded outer edge on said back, and sheets adapted to be aligned by said lower clamping bar and said back, and to be clamped in by said clamping bars with a portion of each sheet visible. 95

11. A loose leaf book, comprising a cover in combination with a plurality of panels hingedly mounted in said cover in overlapping relation from left to right, and sheets in said panels mounted in vertically overlapping relation, each panel comprising a 100 clamp of the tongue and groove type and a back hinged to said clamp adapted to keep the right edges of the sheets in alignment.

12. A loose leaf book, comprising a cover 105 in combination with a plurality of panels hingedly mounted in said cover in overlapping relation from left to right, and sheets in said panels mounted in vertically overlapping relation, each panel comprising a clamp of the tongue and groove type and a back hinged to said clamp adapted to keep the right edges of the sheets in alignment, said sheets each having an ear at one side determining the overlap and a vertical corrugation in said sheet at the same side, as and for the purposes described. 115

13. In a loose leaf binder, a plurality of sheets in overlapping relation lengthwise of the binder, in combination with a binding 120 clamp having a tongue and groove by which said sheets are clamped at their sides.

In testimony whereof I have signed my name to this specification.

JAMES LYON GARFIELD.
